(No Model.)

I. CRUZAN.

WAGON END GATE.

No. 298,831

Patented May 20, 1884.

UNITED STATES PATENT OFFICE.

ISAAC CRUZAN, OF WILLOW SPRINGS, KANSAS.

WAGON END-GATE.

SPECIFICATION forming part of Letters Patent No. 298,831, dated May 20, 1884.

Application filed January 12, 1884. (No model.)

To all whom it may concern:

Be it known that I, ISAAC CRUZAN, a citizen of the United States, residing at Willow Springs, in the county of Douglas and State 5 of Kansas, have invented a new and useful Improvement in Wagons, of which the following is a specification, reference being had to the accompanying drawings.

My invention relates to wagon-bodies, and 10 more particularly to a combined end-gate and platform for the same, to allow of the ready removal of grain, &c., from the wagon; and it has for its object to provide a device of this 15 character which shall be cheap and simple in its construction and effective and durable in its use.

The invention consists in the combination, with a wagon, of a hinged gate or door and other parts, all of which will be hereinafter 20 more fully described, and pointed out in the claim.

In the drawings, Figure 1 is a rear view of 25 a wagon-body having my improved gate applied thereto. Fig. 2 is a perspective view showing the gate in position for the removal of grain. Fig. 3 is a cross-section.

A represents the wagon-body, which is of the usual construction, and having the vertical strips *a* attached to its inner rear end. 30 B represents the end-gate, having the strips *b* attached to its outer side, the same being provided with transverse perforations *b'*, which register with perforations *b*² in the strips *a* and the side-boards of the wagon, the said perforations being adapted to receive bars *b*³ for locking the gate. The gate B is secured to the bottom of the wagon by hinges C, the ends of which are secured to the outer side of the gate B and the bottom of the wagon, respectively. The gate B is provided on its inner side with strips D, which are cut off diagonally; or they may be sloped downwardly from the top of the gate to the floor of the wagon. These strips D are provided on their 45 inner sides with uprights or braces *d*, which, when the gate is lowered, bear against the strips *a*, and thus serve to support the gate. The strips D are provided on their top edges with metal plates *e*, the same extending a short

distance beyond the ends of the said strips, 50 and provided at their ends with perforations *e'*, adapted to receive hooks *e*², which are secured to the inner sides of the side-boards of the wagon.

The operation is as follows: When it is desired to unload a wagon, the locking-bars *b*³ are withdrawn and the gate lowered, as shown in Fig. 2, the braces *d* bearing against the strips, thus serving as a support, and also preventing the escape of grain. The hooks are 60 then secured in the perforations of the metal plates, thus securing a firm fastening and affording a platform for the driver to stand upon while unloading the wagon.

It will be seen that, when desired, the gate 65 as above described may be dispensed with by simply removing the hinges which secure it to the floor of the wagon-body, and the ordinary end-board used in lieu thereof.

It will also be obvious that the improvement as above described is simple in its construction, may be readily applied, and affords 70 convenient means for either loading or unloading a wagon, affording a platform for the driver, and allowing him ready access to the 75 contents of the wagon.

Having fully described my invention, what I claim as new, and desire to secure by Letters Patent, is—

The combination, with a wagon-body having vertical strips *d* secured to its inner sides, adjacent to the ends thereof, of a gate, B, hinged to the floor thereof, and provided with side strips, D, having plates *e*, provided at their forward ends with openings or perforations to 80 receive the ends of hooks pivoted to the inner sides of the wagon-body, strips secured to the outer sides of said gate, near the end thereof, and having openings registering with openings *f* in the sides of the wagon-body, for the 85 passage of rods *b*³, substantially as set forth.

In testimony that I claim the foregoing as my own I have hereto affixed my signature in presence of two witnesses.

ISAAC CRUZAN.

Witnesses:

JOHN W. SWIMLEY,
FRANK ROOKS.
